ASH TRAY

Harry W. Hollister, New York, N.Y., assignor of a fractional part interest to Betty Mabel Coester, New York, N.Y.

Filed Nov. 14, 1969, Ser. No. 20,095

Term of patent 14 years

Int. Cl. D27—03

U.S. Cl. D85—2

FIG. 1.

FIG. 2.

FIG. 1 is a perspective view of an ash tray embodying my new design; and

FIG. 2 is a perspective view showing the side opposite that seen in FIG. 1.

I claim:

The ornamental design for an ash tray, substantially as shown.
